G. P. Gopel

UNITED STATES PATENT OFFICE.

ARTHUR E. BELLIS, OF SPRINGFIELD, MASSACHUSETTS, ASSIGNOR TO COLLINS AND BONNELL, INC., OF NEW YORK, N. Y.

CRUCIBLE.

1,858,816.

Specification of Letters Patent. Patented Nov. 16, 1920.

Application filed December 10, 1916. Serial No. 343,769.

To all whom it may concern:

Be it known that I, ARTHUR E. BELLIS, a citizen of the United States, and resident of the city of Springfield, county of Hampden, State of Massachusetts, have invented certain new and useful Improvements in Crucibles, of which the following is a specification.

This invention relates to crucibles such as are used in the heat treatment of metals, and has for its primary object to provide a crucible for containing metallic salt baths, which is of such construction that its life or period of serviceability will be materially prolonged.

In the use of metal pots or crucibles for heating salt baths in the heat treatment of metals, a distress in the physical structure of the crucible is usually experienced at the higher temperatures by the oxidizing atmosphere attacking the exterior of the pot walls. On the other hand, when the crucible is constructed of commercial graphite or other refractory material, a distress in the structure of the crucible is also caused at the higher temperatures by the action of the salts on the refractory material which causes it to spall or flake off on the interior of the crucible wall.

My present invention aims to eliminate the above disadvantages incident to the use of crucibles constructed of metal or refractory materials, and which greatly limits the life of the crucible. To this end, therefore, I have provided a pot or crucible having an external shell of refractory material and an internal shell or lining of ferrous metal. Thus, the metal lining prevents the harmful action of the chemical salts above referred to, while the refractory outer shell is neutral to the effects of oxidizing atmosphere.

In the accompanying drawing wherein I have illustrated one practical embodiment of my invention, the figure represents a vertical sectional view through a furnace having the improved pot or crucible arranged therein. Further objects and advantages of my invention will become apparent from the following description.

Referring in detail to the drawing, 5 designates a furnace which may be of any conventional or approved form. A pedestal 6 rises centrally from the base wall of this furnace.

The pot or crucible, as herein shown, com-

prises an outer wall or shell 7 having a flattened base wall for engagement upon the pedestal 6. This shell gradually flares or increases in diameter to its upper end. The shell 7 may be constructed or molded of graphite or other suitable refractory material.

Within the external shell 7 of the crucible an internal shell or lining 8 of metal is arranged. This lining may be of any suitable base metal alloy, such as steel, wrought iron, cast iron, or other ferrous metals. This internal shell has a rounded or convex base portion contacting at its center upon the flattened base of the external shell 7. The shell 8 is of such diameter that its wall is spaced from the wall of the external shell 7, so as to afford ample room for the expansion of the metal shell. At this upper end the internal metal shell 8 is provided with an annular laterally extending flange 9, which extends over the upper edge of the external refractory shell 7 and rests upon the top surface of the furnace 5.

The metal lining or shell 8 may, when necessary, be readily removed from the outer refractory shell of the crucible, in order to effect a thorough cleaning of the same, or, when it is necessary to provide the crucible with a new lining.

The furnace 5 is equipped with burners 10, which may be of any preferred type, and are arranged at either side of the pedestal 6 below the external shell 7.

From the above description, it will be apparent that the bath salts do not come into contact with the external refractory shell of the crucible, while the metallic internal shell or lining does not come into contact with the products of combustion and it is not subject to the oxidizing effects of atmospheric oxygen circulating through the furnace.

It has been successfully demonstrated in practice that a pot or crucible of this improved construction has a life or period of serviceability which is considerably longer than the life of either a metallic pot or refractory crucible as heretofore used. Accordingly, by means of the present improvement, a great saving may be effected in the cost of such pots or crucibles. Furthermore, it has been found that the salt bath may be permitted to freeze in the internal metallic shell without distress of its physi-

cal structure. The necessity of laboriously baling out the salts while in a liquid state is thus obviated with a commensurate saving of time and labor.

5 From the foregoing description, considered in connection with the accompanying drawing, the construction, manner of use and several advantages of the present invention will be fully understood. The pot or crucible can, of course, be constructed in many different shapes and sizes for use in connection with various types of furnaces, and it is to be understood that the disclosure in the accompanying drawing is merely 10 illustrative of one practical concept of the invention. The initial cost of construction and installation is relatively small in comparison with the saving which is realized by the greatly increased period of usefulness of 15 the crucible, so that replacement by a new crucible is required at infrequent intervals.

I have above described what I have found to be a very practical and satisfactory embodiment of the invention, but it is to be understood that the crucible may also be exemplified in numerous other alternative constructions, and I accordingly reserve the privilege of adopting all such legitimate changes as may be fairly embodied within 20 the spirit and scope of the invention as claimed.

I claim:

1. A crucible having an external wall

more or less resistant to the attacks of oxidizing atmospheres, and a removable non-refractory lining for said wall neutral to the action of chemical salts.

2. A crucible having an external wall more or less resistant to the attacks of oxidizing atmospheres, and an inner wall of non-refractory material adapted to be positioned within said external wall, and protected thereby from the attacks of oxidizing atmospheres, said internal wall being removable without disturbing the external wall, in order to discharge its contents, and adapted to be then replaced within the external wall to receive a new charge.

3. A crucible having an external wall of non-oxidizing material, and a removable base metal lining for said wall.

4. A crucible consisting of a removable ferrous metal internal shell and an external shell of refractory material.

5. A crucible consisting of a non-oxidizing external shell and an internal ferrous metal shell neutral to the action of chemical salts and having its wall spaced from the wall of the external shell.

6. A crucible consisting of an external shell of refractory material, and an internal ferrous metal shell having its wall spaced from the wall of said external shell.

In testimony that I claim the foregoing as my invention I have signed my name.

ARTHUR E. BELLIS.
